PRIMARY CONTROL FOR BURNERS

John J. Rothwell and Paul Schell, Elkhart, Ind.,
assignors to Penn Electric Switch Co., Goshen,
Ind., a corporation of Iowa

Application September 6, 1946, Serial No. 695,134

16 Claims. (Cl. 158—28)

1

Our present invention relates to an oil burner control or the like, wherein a so called "primary control" is in the form of a unit to be installed on the oil pipe in an oil burner nozzle, instead of utilizing the usual stack switch in the stack and wherein there is a so called "slip connection," the present application being a continuation-in-part of our co-pending application Serial No. 634,968, filed December 14, 1945.

One object of our invention is to provide a combined combustion switch and safety switch incorporated in the same control unit, which unit may be connected in a burner control circuit in a simple manner so as to deenergize the relay closed circuit of the motor switch as a result of combustion failure either initially or after establishment and further upon failure of a safety heater of the primary control such as a burnt out condition of such heater.

Another object is to provide a primary control that is simple and compact in construction and inexpensive from a manufacturing and installation standpoint, the control requiring no cutting into the furnace or stack and being so designed as to not interfere with the operation of the usual "gun" type of oil burner when installed in its nozzle.

A further object is to provide a controller arranged to respond directly to the heat of combustion by exposing a bimetal element thereof to heat in the combustion chamber as radiated back from the burner flame at the discharge end of the burner nozzle, the bimetal being located within a few inches of the discharge end of the nozzle so as to minimize the area of bimetal required for satisfactory operation of the control unit.

Still a further object is to provide a primary control unit in the form of a housing of small size mounted on the oil pipe of the burner and surrounding it so that there is room around the exterior of the housing for relatively free passage of air from the blower to the discharge end of the burner nozzle, a safety heater and a bimetal element responding thereto being located within the housing, the bimetal element being torus shaped to substantially surround the oil pipe and thereby contribute to compactness, the bimetal element having a portion that is directly exposed through an opening in the housing to direct heat from the flame at the discharge end of the nozzle.

An additional object is to provide a combustion switch which utilizes a torus shaped bimetal element in such manner that the single element responds to two different conditions, (1) the combustion heat and (2) the heat from an electrically

2

energized heater, the parts being associated in a control circuit so that the desired opening of the circuit is had upon combustion failure either prior to or subsequent to combustion establishment, and the bimetal being so housed that the ambient temperature surrounding it is stabilized within the housing by the passage of air thereover.

Another additional object is to provide a means to correct for the movement of the bimetal element so that a safety shut-down operation occurs as quickly on a hot-flame failure as it does on a cold-start failure or may be arranged to occur more quickly, thus securing the most satisfactory timing of the primary control for shut down after (1) a long operating period of the furnace (2) a short operating period thereof or (3) non-operation from a cold start, this being accomplished by means of a second bimetal element operating a shutter to variably shield the section of the bimetal element that responds to combustion flame from such flame.

With these and other objects in view our present invention consists in the construction, arrangement and combination of the various parts of a primary control to attain the objects contemplated as well as others which will hereinafter appear in accordance with the following specification taken in conjunction with the accompanying drawings wherein;

Figure 1 is a vertical sectional view through the flame end of a gun type oil burner showing the burner nozzle (or oil tube and oil nozzle), our primary control being mounted on the oil pipe to the oil nozzle and an electric diagram being included to show the relation of our primary control in a burner circuit controlled thereby.

Figure 2 is an enlarged front elevation of the primary control and shows the oil pipe in cross section as taken on the line 2—2 of Figure 1.

Figure 2a is a diagrammatic view illustrating the portion of a bimetal element that is exposed to combustion heat in Figure 2.

Figure 3 is a side elevation of Figure 2 looking from left to right and showing the housing of the primary control in section.

Figure 4 is a sectional view on the line 4—4 of Figure 3 showing particularly the torus shaped bimetal element.

Figure 5 is a perspective view of a bimetal element for operating the shutter shown in the upper part of Figure 2.

Figure 6 is a bottom plan view of Figure 3 with the housing for the control shown in section, the bimetal element being shown as warped into

50

45

55

the position it assumes in response to heat from both an electrical heater and from a combustion chamber, and

Figure 7 is a similar view showing only parts of Figure 6 and illustrating the bimetal warped as a result of electrical heat only, the circuit through the primary control being shown diagrammatically in this figure.

On the drawings we have used the reference character B to indicate a mounting base, which 10 base is preferably formed of insulating material. The base B is in the form of a disc around which a raised bead 10 is formed. The base B has a central opening in which a sleeve 12 is pressed. The sleeve is of such size that it can slip over an 15 oil pipe 14 of an oil burner. The pipe 14 as shown in Figure 1 terminates in an oil spray nozzle 16 and the oil pipe is supported along the center of an air tube 18 of the burner.

Air is supplied to the air tube 18 from a blower 20 operated by a blower motor BM in the usual manner commonly known in the oil burner art. The air tube 18 and the oil nozzle 16 together are usually referred to as a "burner nozzle." The burner just described is usually referred to as 25 being of the "gun type" and the oil is sprayed from the nozzle 16 and ignited by suitable electrodes (not shown) receiving high tension from an electrical ignition mechanism shown diagrammatically in Figure 1 as Ign.

The tube 18 projects into a combustion chamber of a furnace, the wall of which is shown at 20 and this wall is usually lined with refractory 22. The primary control is telescopically mounted on the oil pipe 14 leading to the oil nozzle 16 and retained in position relative thereto by a set screw 26.

Cooperating with the base B is a housing in the form of a cup shaped element 28 against the front of the bead 10 and a cup shaped element 30 of insulation against the back of the base B. Within the housing section 28 we mount a torus-shaped bimetal element A as by anchoring one end to a rigid post 32 by means of a screw 34, the post being fixed relative to the base B. The bimetal, it will be noted, substantially surrounds the sleeve 12 which makes for compactness of design and yet secures considerable length for the bimetal element.

The bimetal element A may be considered as having three sections 38, 40 and 42. The section 38 is the one that is anchored at one end by the screw 34. The section 38 may be considered as a combustion responsive section because it is open to flame at the discharge end of the burner air tube 18. The opening to permit radiant heat from the flame to impinge the section 38 is defined by the housing 28 which has the lower half closed by a wall 36 that terminates in a half circle flange 37, as shown in Figure 2. The ends of the flange 37 diverge as at 39 and have vertical portions 41 at their ends which merge into the cylindrical wall 43 defining the periphery of the housing 28. The opening for the flame is that defined by the upper half of the sleeve 12, the flanges 39 and 41 and the upper part of the cylindrical wall 43 extending between the upper ends of the flanges 41.

The section 40 of the bimetal element A may be considered relatively non-warping because of a pair of flanges 46 and 48 formed along its inner and outer edges. The section 42 of the element A may be considered as a heater section, it being adjacent a channel-shaped electric heater support 44 having its open side toward the bimetal ele-

ment A. A heater comprising a resistance coil 45 lays in the support 44 and the support has a pair of posts 47 for mounting it on the base B.

The heater 45 has one end connected as at 52 to the mounting post 32 and its other end connected by a wire 53 to the relay coil RC in Figure 1. The circuit for the heater 45 passes from the post 32 through the bimetal element A to a contact 54 carried thereby, which contact is normally engaged with a stationary but adjustable contact 55. The contact 55 is connected by a wire to the room thermostat RT. Obviously the bimetal element A can be made to operate a separate switch as shown in our copending application, Serial No. 634,968, filed Dec. 14, 1945 instead of being part of the switch as herein disclosed.

The wires 53 and 56 are part of a room thermostat circuit including the room thermostat and relay coil already referred to, the current for the circuit being supplied by a secondary S of a transformer T. The primary P of the transformer is connected across line wires 70 and 72 which supply current for the burner motor BM and for the ignition mechanism Ign. The burner motor and the ignition mechanism are both under control of a motor switch MS which is normally open, and is closed by the relay coil whenever it is energized.

Within the lower part of the housing 28 a second bimetal element C is provided, this element being anchored at one end in a slot of a post 73 which post extends through the wall 36 of the cover 28 and terminates in a slotted end 74 for adjustment purposes. A lock nut 75 is provided 35 to retain the adjustment. The bimetal element C has an operating arm 76 perforated at 77 to receive the lower end of link 78.

A pivot rod 79 extends through the flanges 41 and spans the distance between them. Pivoted 40 thereon is a damper blade 80 having a pair of pivoted ears 81 and 82 at its opposite ends. The ear 82 has an extension 83 receiving the upper end of the link 78 whereby up and down motion of the bimetal arm 76 will cause up and down motion 45 of the extension 83 and resultant motion of the blade 80 from a cold position shown by solid lines in Figure 3 to a hot position shown by dotted lines.

PRACTICAL OPERATION

Normal burner operation

In the operation of our invention, when the parts are in the cold position of Figure 3, the contact 54 is held against the contact 55 by 55 tension in the bimetal element A as determined by adjustment of the contact 55. This results in the room thermostat circuit being closed across the wires 53 and 56. The secondary circuit of the transformer T is thereby ready for 60 operation whenever the room thermostat RT closes. When it does close, then the relay coil RC is energized so that the motor switch MS closes for operating the burner, and the heater wire 45 is energized because of the energization 65 of the room thermostat circuit in which the heater is in series.

Energization of the heater wire 45 causes the bimetal portion 42 to become warped or curved and at the same time heat from the flame of 70 the burner passing through the opening defined by the elements 12, 39, 41 and 43 effects similar warpage of the bimetal section 38 as in Figure 6 (solid lines). The dotted lines in this figure illustrate the cold position of the bimetal element. Since both bimetal element sections 38

and 42 are warped, the unanchored section 42 will assume approximately the same curvature as the anchored section 38 as shown by the solid lines thus keeping the contact 54 in engagement with the contact 56.

The combustion chamber temperature will now rise and will cause some rise in temperature ambient to the base B and the housing section 28. This general rise in ambient temperature will cause the bimetal element A to assume an even sharper curvature than that shown in Figure 6 until a maximum temperature is reached if some means is not provided to cut down the heat from the flame. In many tests we have found that such maximum temperature does not exceed approximately 260° F. and therefore the primary control is not heated to a prohibitively high degree as when a combustion switch is located in the stack of a furnace. Therefore lower temperature bimetals may be used and are found more reliable over a long period of time as they are not subjected to undesirable great temperature fluctuations that change the set in bimetal elements.

After the burner has been operating a few minutes, the second bimetal element C will start unwinding, thereby causing the arm 76 to be elevated with the degree of elevation increasing with a rise in temperature. This will swing the damper blade 80 from the inoperative position shown by solid lines in Figure 3, toward the operative position shown by dotted lines, and after some further temperature rise the dotted position will be reached and the damper can no longer move because of a stop 86 thereon engaging the bottom of a notch 87 some time before the maximum temperature of 260° has been attained.

In the operative position of the damper, it considerably cuts down the effect of the flame on the bimetal element section 38 as the opening from the flame to the bimetal is now defined by the areas 88 and 90 illustrated in Figure 2a, 90 being an opening provided in the damper blade if found necessary due to the blade offering too much shielding effect. Obviously the size of this opening also enters into the operation of the device as the size can be changed to meet requirements and the desired results obtained.

Failure of combustion to be established

Referring to Figure 7, if combustion does not occur in the normal manner, the bimetal element section 42 will be heated by its heater 44, thus bending as shown but since there is no flame from the burner there is no heat passing through the opening in the housing 28 to impinge the bimetal element section 38. It accordingly will remain straight and we have a resulting separation of the contact 54 from the contact 55 thus breaking the circuit of the relay coil RC so that the motor switch MS drops open and thereby shuts down the burner.

Combustion failure after establishment

In the event that combustion is successfully established and then fails, the section 38 of the bimetal element A will straighten out from its curved position as shown by full lines in Figure 6 (sections 38 and 42 being similarly curved) and assume the position of Figure 7 which causes the contact 54 to leave the contact 55 because of the section 42 still being curved on account of heat from the heater 44. If the burner has operated only a few minutes, the shut down

period will have one definite length, whereas if the burner has been operating for a considerable length of time, this period will be substantially the same length due to the damper blade 80 being in the dotted position of Figure 3. If a shorter timing period following long burner energization is desired, the shielding effect of the damper blade can be increased.

By mounting both of the bimetal element sections 38 and 42 within the housing section 28, they are in substantially the same ambient temperature which may fluctuate anywhere between a cold start temperature and temperature attained by long running of the burner, for instance 260° F. Therefore, the bimetal element is self-compensating for any temperature that it encounters, as ambient temperature affects both sections 38 and 42 equally and merely causes more or less warping without change in the position of the actuating end 42 relative to the anchored end 38. The section 42, however, is additionally responsive to the heater 44, whereas the section 38 is additionally responsive to combustion temperature whereby the two sections are brought out of step as indicated by the position of Figure 7 whenever there is combustion failure, either initially or subsequent to successful establishment thereof.

Our arrangement also is not affected by the flow of air around the primary control within the air tube 18 as any air flow increase or decrease is automatically compensated for as it merely changes the temperature ambient to the bimetal element A and permits the element to warp more or less, with the anchored and actuated ends remaining in step.

The single set of contacts 54 and 55 connected as they are in the room thermostat circuit takes the place of both the safety switch contacts and the combustion switch contacts in the usual type of stack switch having a thermal responsive element in the stack, and a safety switch including a heater therefor. In our arrangement, the one bimetal element A responds to both an electrical heater and to temperature in the furnace in such manner that a single set of contacts serve as a safety control in response to combustion and in response likewise to failure of the heater 44 such as burning out thereof. Whenever it does burn out, then the room thermostat circuit is open of course and cannot be reclosed until the heater coil is renewed.

Our primary control herein disclosed effects opening of the circuit at the contacts 54 and 55 whenever two events occur at the same time. That is, when the heater 44 is heated and the section 38 of the bimetal element is not heated by combustion. Thereupon, the burner is shut down, whereas during normal cycling of the burner the contacts remain engaged and are never separated. Separation occurs only when there is either an initial or a subsequent flame failure.

Our arrangement eliminates the necessity and use of so called "slip connections," in the usual type of stack switch. It has been found very satisfactory in operation throughout rather wide variations in combustion chamber temperatures, and other variable temperature factors may occur without producing a false shut-down by operation of the primary control. The housing of the bimetal element A, and its shape so that it surrounds the oil pipe 14, permit compactness and minimize the overall diameter of the control so as not to interfere with flow of air from

the burner to the flame. At the same time the bimetal element is properly responsive to ambient temperature so that variation therein does not produce a false shut-down operation and such variations may be considerable, and yet the desired shut-down operation will occur whenever there is flame failure from any cause.

The damper blade 80 operated by the second bimetal element C solves very nicely in one way the undesirable characteristic of maximum attainable temperature warping the bimetal element A so far that it considerably lengthens the shut down timing upon flame failure after combustion establishment following a long running period of the burner. The rate of travel of the thermostatically operated arm and the size and shape of the damper blade 80 may be varied to secure the desired results and where the damper has too much shielding effect this can be reduced to the desired degree as by the use of the opening 90.

While we have shown in the present application direct contact of the contact 54 with the contact 55, the bimetal element A may operate a switch that remains in the open position after once assuming that position as in our copending application above referred to. Thus the burner control is operable to shut down the system upon flame failure until such time as the switch is reset in the closed position instead of serving merely as a means to provide a purging period during a temporary shut-down period that is terminated by the element A cooling down to normal position and effecting re-engagement of the contact 54 with the contact 55.

Changes may be made in the construction and arrangement of the parts of our device without departing from the real spirit and purpose of our invention, and it is our intention to cover by our claims any modified forms of structure or use of mechanical equivalents which may be reasonably included within their scope.

We claim as our invention:

1. A primary control for burners comprising a base member adapted to be mounted on an oil pipe in an oil burner nozzle, a torus-shaped bimetal element adapted to surround the oil pipe and mounted on said base, said bimetal element having one end anchored, and the other end free and constituting an actuating element, a combustion switch having switch contacts which are controlled by said actuating element, an electric heater for said bimetal element to effect warpage of substantially one-half thereof, the other half being adapted to be responsive to direct heat from the flame issuing from the oil burner nozzle, a housing around both halves of said bimetal element and adapted to surround the oil pipe, said housing adapted to be subject to ambient temperature within the burner nozzle and having an opening through which heat from the flame is adapted to pass to the bimetal element, a normally inoperative damper in said opening, and thermally responsive means in said housing adapted to move said damper to an operative position shielding said bimetal element partially from the flame after the burner operates a sufficient length of time for raising the temperature surrounding said primary control to a point somewhat below maximum attainable temperature.

2. A primary control for burners comprising a base member adapted to be mounted on an oil pipe in an oil burner nozzle, a torus-shaped bimetal element adapted to surround the oil pipe

and mounted on said base, said bimetal element having one end anchored, and the other end free and constituting an actuating element, a combustion switch having switch contacts which are controlled by said actuating element, an electric heater for said bimetal element to effect warpage of substantially one-half thereof, the other half adapted to be responsive to direct heat from the flame issuing from the oil burner nozzle, a normally inoperative damper between the flame and said bimetal element, and thermally responsive means adapted to move said damper to an operative position shielding said bimetal element partially upon temperature rise.

5 3. A primary control for burners comprising a base member adapted to be mounted in an oil burner nozzle, a bimetal element mounted on said base, said bimetal element having one part anchored, and another part free and constituting an actuating element, a combustion switch having switch contacts which are controlled by said actuating element, an electric heater for said bimetal element to effect warpage of one of said parts, the other of said parts adapted to be responsive to direct heat from the burner flame, a normally inoperative damper between the flame and said last mentioned bimetal part, and thermally responsive means adjacent the flame adapted to move said damper to an operative position shielding said bimetal element partially from the flame after the burner operates and before it attains a stable temperature.

10 4. A primary control for burners comprising a base member adapted to be mounted in an oil burner nozzle, a bimetal element mounted on said base, said bimetal element having one part anchored, and another part free and constituting an actuating element, a combustion switch having switch contacts which are controlled by said actuating element, an electric heater for said bimetal element to effect warpage of one of said parts, the other of said parts being adapted to be responsive to direct heat from the burner flame, and means adapted to reduce heat flow from the flame to said other of said bimetal parts as the combustion chamber temperature rises.

15 5. A primary control for burners comprising a housing adapted to be mounted in an oil burner air tube and having an opening, a torus-shaped bimetal element within said housing, said bimetal element having one end anchored, and its other end free and constituting an actuating element, switching mechanism controlled by said actuating element, an electric heater for said bimetal element to effect warpage of one portion thereof, another portion thereof being adapted to be responsive to direct heat from the flame issuing from the oil burner air tube and passing through said opening to impinge said another portion, and heat responsive means adapted to partially shield said opening against the passage of heat therethrough as the overall temperature of said primary control increases.

20 6. In a control of the character disclosed, a housing adapted to be mounted in an oil burner air tube and having an opening, a bimetal element within said housing, said bimetal element having one end anchored, and its other end free and constituting an actuating element, switching mechanism controlled by said actuating element, an electric heater for said bimetal element to effect warpage of one portion thereof, another portion thereof being adapted to respond to direct heat from the combustion flame, and burner heat responsive means adapted to at least partially

shield said opening against the passage of heat therethrough as the temperature of said control increases.

7. A primary control of the character disclosed comprising a housing adapted to surround an oil pipe within a burner nozzle and located within a few inches of the flame end of the nozzle, a U-shaped bimetal element within said housing, means adapted to shield one arm of said bimetal element from the flame, said housing having an opening for direct heat rays from the flame to the other arm of said bimetal element, an electrical heater for the shielded arm of said bimetal element, and temperature responsive means adapted to decrease the effective size of said opening as the temperature within said burner nozzle increases.

8. A control structure comprising a housing adapted to be mounted in a burner nozzle adjacent the flame end of the nozzle, a U-shaped bimetal element within said housing, means adapted to shield one arm of said bimetal element from the flame, said housing having an opening for direct heat rays from the flame to the other arm of said bimetal element, an electrical heater for the shielded arm of said bimetal element, and temperature responsive damper means adapted to choke the size of said opening as temperature increases within said burner nozzle.

9. In a burner control device for a burner system having a burner motor and a switch for operating said burner motor, means adapted to respond to room temperature for effecting closure of said switch, a control circuit adapted to be controlled by the room temperature responsive means and having said control device connected therein, said control device comprising a switch, a heater and a thermal element, a housing therefor, said switch being controlled by said thermal element and its contacts engaged when two individual sections of the thermal element are both heated, said sections being adapted to respond to ambient temperature within said housing, said housing adapted to be located in a burner air tube and having an opening, one of said sections being adapted to respond through said opening to heat from the flame at the end of the air tube, the other section being responsive to heat from said heater, said sections when so responding moving in the same direction and maintaining the contacts of said switch closed whereby heat of the heater and reduction or omission of heat from the flame effects opening of said contacts, means adapted to effect a decrease in the timing for shut-down when the ambient temperature is high comprising a damper blade located in said opening and variably shielding the same, and means to vary the position thereof to increase the shielding effect thereof as the temperature increases, said last means being thermally operated by means of a temperature responsive element located within said housing.

10. In a burner control device for a burner system having a burner motor and a switch for operating said burner motor, means adapted to respond to room temperature for effecting closure of said switch, a control circuit adapted to be controlled by said room temperature responsive means and having the control device connected therein, said control device comprising a switch, a heater and a thermal element, a housing therefor, said switch being controlled by said thermal element and its contacts engaged when two individual sections of the thermal element

are both heated, said housing adapted to be located in a burner air tube and having an opening, one of said sections adapted to respond through said opening to heat from the flame at the end of the air tube, the other section being responsive to heat from said heater, said sections when so responding moving in the same direction and maintaining the contacts of said switch closed whereby heat of the heater and reduction or omission of heat from the flame effects opening of the contacts, and thermally responsive means located in said burner air tube and affecting said other section for effecting a decrease in the timing for shut-down as the ambient temperature increases.

11. A burner control device of the character disclosed comprising a combustion switch adapted to surround an oil pipe of a burner and located within a few inches of the flame, a thermal element, said combustion switch having contacts controlled by one end of said thermal element, the other end of said element being anchored, said thermal element comprising two arms both of which are adapted to be subject to ambient temperature, a housing shielding one of said arms, an electric heater for said arm, said housing having an opening through which heat from the flame is adapted to impinge the other arm, temperature responsive means responding to the temperature within said housing for varying the size of said opening, decreasing its size with an increase in temperature, said arms when responding to a normal burner operating condition adapted to work equally to maintain said contacts closed whereby heating of the heating element heated arm and a cool or cold condition of the flame heated arm is adapted to move the arms unequally to effect separation of said contacts.

12. A burner control device comprising a combustion switch adapted to be mounted in a burner tube adjacent its discharge end, a thermal element in said combustion switch, said combustion switch having contacts controlled by one end of said thermal element, the other end of said element being anchored, said thermal element comprising two arms, a housing shielding one of said arms, an electric heater for said arm, said housing having an opening through which heat from the flame is adapted to impinge the other arm, and temperature responsive means adapted to decrease the size of said opening with an increase in temperature in the burner tube.

13. In a burner control device, a combustion switch comprising a pair of thermal element sections arranged in series with one end anchored, contacts controlled by the other end thereof, and a heating element, said contacts being normally in an operative position and remaining so as both of said sections are adapted to warp in response to indirect flame temperature, one of said sections additionally warping in response to heat thereto from the heating element and the other of said sections adapted to additionally warp in response to heat thereto directly from the flame for thereby effecting retention of said sections in operative position, a cooling or cold condition of the flame affected section adapted to render said contacts inoperative, and temperature responsive means adapted to reduce the effect of the flame on the thermal element as the temperature surrounding said burner control device rises.

14. In a burner control device, a combustion

switch comprising a pair of thermal element sections arranged in series with one end anchored, contacts controlled by the other end thereof, and a heating element, said contacts being normally in an operative position and remaining so as both of said sections are adapted to warp in response to indirect flame temperature, and adapted to additionally warp in response to heat to one of said sections from the heating element and directly from the flame to the other one which effects retention of said contacts in operative position, a cooling or cold condition of the flame affected section rendering said contacts inoperative, and temperature responsive means adapted to reduce the effect of the flame on the thermal element as the temperature of the burner rises.

15. In a primary burner control device, a combustion switch comprising a pair of thermal element sections arranged in series with one end anchored, contacts controlled by the other end thereof, and a heating element, said contacts being normally closed and remaining closed as both of said sections are adapted to warp in response to indirect flame temperature, and adapted to additionally warp in response to heat to one of said sections from said heating element and to the other section direct from the burner flame, thermal responsive means adapted to reduce the action of the burner flame on said other section as the temperature surrounding said control device rises, and a cool or cold flame condition adapted to effect less warpage of said direct

5
10
15

flame heated section for opening said contacts for the purpose of shutting down the burner.

16. In a burner control unit, a combustion switch comprising a pair of thermal element sections arranged in series with one end anchored, contacts controlled by the other end thereof, and a heating element, said contacts being normally closed and remaining closed as both of said sections are adapted to be heated equally due to general temperature rise in the burner, and adapted to additionally warp in response to heat to one of said sections from said heating element and to the other section direct from the burner flame, and thermal responsive means adapted to reduce the direct action of the burner flame on said other section as the temperature surrounding said control unit rises.
